CLAIM

The ornamental design for a vehicle cargo anti-slide bracket, as shown and described.

DESCRIPTION

FIG. 1 is a perspective view of an anti-slide bracket.

FIG. 2 is an elevational view of a pair of anti-slide brackets secured together with hook and loop fasteners.

FIG. 3 is an environmental perspective view a heavy box maintained in position by three pairs of anti-slide brackets, each pair similar to those shown in FIG. 2, and each pair of brackets secured together; and,

FIG. 4 is an environmental perspective view of cargo held in a rear corner portion of a storage area by two anti-slide brackets.

The broken lines are included for the purpose of illustrating environment and form no part of the claimed design.
